UNITED STATES PATENT OFFICE.

ALFRED T. KELLIHER, OF SALEM, OREGON.

FENCE.

No. 824,874.

Specification of Letters Patent.

Patented July 3, 1906.

Application filed August 5, 1905. Serial No. 272,911.

To all whom it may concern:

Be it known that I, ALFRED T. KELLIHER, a citizen of the United States, residing at Salem, Oregon, have invented certain new and useful Improvements in Fences, of which the following is a specification.

My invention relates to iron fence-posts; and the object of the invention is to provide means for firmly holding the posts in the ground.

The invention is illustrated in the accompanying drawings, in which—

Figure 1 is a view showing two posts with their supporting means and with the wires secured to the posts. Fig. 2 is a part-sectional view on the line 2 2, Fig. 1. Figs. 3, 4, 5, and 6 are plan views with the post in section of different forms of anchors. Fig. 7 is a view taken on the line 7 7 of Fig. 6. Fig. 8 is a plan view showing means for securing top boards to the post, and Fig. 9 is a view on line 9 9 of Fig. 8.

In the drawings, A indicates the metal post having notches B therein, in which the wires C are adapted to be placed. After the wires are placed in the said notches the metal is bent over, as shown in Fig. 2, to hold the wires in the notches. As shown, the post tapers from its lower end upwardly, so that the upper end thereof is smaller than the lower end.

To hold the posts firmly in position, I provide suitably-shaped anchors D, to which the posts are secured.

Fig. 3 shows one form of anchor used in connection with the post. In this figure a sheet of metal has its ends bent at right angles in opposite directions so as to form wings F G, and intermediate said wings a loop E is formed in the metal and the inner sides of the loop pressed against each other. Thus an angular projection is formed against one side of which the lower part of the post is

placed and secured thereto by the bolts and nuts or rivets.

The anchor shown in Fig. 4 is like that shown in Fig. 3 with the exception that only one wing F' is formed thereon.

The anchor shown in Fig. 5 differs from that shown in Fig. 3 simply by having the portions between the loop and wings curved instead of straight.

Instead of securing the post to one side of the projection formed by the looped metal I may form an open loop E", Fig. 6, and by providing a slot H in the lower part of the post, in which a part of the loop engages, the post will be held by the loop alone, as shown in Figs. 6 and 7.

Figs. 8 and 9 show a post provided with a forked end, between the forks of which may be placed the boards I K when it is desired to use boards at the top of the fence.

It will thus be seen that when the dirt is packed around the anchor all turning and lateral movement of the post will be prevented.

Having thus described my invention, what I desire to claim is—

1. A fence-post of rectangular form and an anchor having an intermediate looped portion to which the post is connected, said looped portion having its sides straight and parallel to the sides of the post.

2. A fence-post, an anchor having an intermediate looped portion extending at right angles to the anchor, the limbs of the loop being brought together, means for securing the post to the said loop portion and wings on the said anchor.

In testimony whereof I affix my signature in presence of two witnesses.

ALFRED T. KELLIHER.
